UNITED STATES PATENT OFFICE.

FRANK PELC AND STEFANIA PELC, OF McDONALD, PENNSYLVANIA.

BEEHIVE.

1,344,817.

Specification of Letters Patent. Patented June 29, 1920.

Application filed May 24, 1919. Serial No. 299,483.

To all whom it may concern:

Be it known that I, FRANK PELC, a citizen of Poland, residing at McDonald, county of Washington, and State of Pennsylvania, and I, STEFANIA PELC, a citizen of Poland, residing at McDonald, county of Washington, and State of Pennsylvania, have invented certain new and useful Improvements in Beehives, of which the following is a specification.

This invention relates to improvements in bee hives, such as are used by apiarists in which to gather honey.

The principal object of the invention is to provide a bee hive containing a plurality of plates upon which the bees may build their combs, means being provided whereby the plates are spaced uniformly one from another, and which may be readily removed from the hive when desired.

These and various objects of like character, which will be more fully apparent as the description progresses, are attained by the novel construction and combination of parts hereinafter described, and shown in the accompanying drawings, forming a material part of this disclosure, and in which—

Figure 1 is a perspective view showing a bee hive made in accordance with the invention, the walls being broken away in order to disclose the interior construction.

Fig. 2 is a partial vertical sectional view taken through the hive.

Fig. 3 is a fragmentary plan view of one of the plates as combined with the spacing elements.

Fig. 4 is a side elevational view of the same.

Fig. 5 is a plan view of one of the plates in detail, and

Fig. 6 is an edge view thereof.

Referring to the drawings, the bee hive is shown to be formed rectangularly and comprised of double walls at the sides, back and bottom. The outer walls 10 are separated from the inner walls 12 by spaces 11, while the front side is normally covered by a double door 14, constructed in a similar manner, and disposed over the bee hive is a removable roof 15, which upon being raised gives access to the entire interior.

Extending longitudinally within the hive, and affixed to the inner side walls 12, at about the center of their height, are cleats 16, similar cleats 17 being secured parallel to the upper end walls of the structure and also near the bottom.

A plurality of rectangular plates 18 are

formed with recesses 19 in their edges adapted to engage with the cleats 16 so as to be suspended therefrom, the upper edge of the plates 18 containing central grooves 20, receptive of tongues 21, formed with short strips 22, carried in heads 23, adapted to rest upon the upper cleats 17, the corners at the lower edges of the plates being removed 65 so as to permit engagement with the lower cleats.

In order to maintain the plates 18 at a proper distance one from another, knobs or similar extensions 25 are formed substantially at their centers adapted to make contact with the adjacent plates when disposed in a row within the hive.

Used either in combination with the plate 18 or as fillers at the ends of the hive, are rectangular frames 28, having lateral projections 29 upon their lower elements while their upper elements are engaged by hinges 31, to strips 32, acting as spacers for the same. A platform 36 extends outwardly from the door opening upon which the bees 80 may alight.

From the foregoing it will be seen that a bee hive containing a plurality of movable comb filling plates has been disclosed and the same may be adjusted to suit the number of bees inhabiting the hives, or, as they become filled, removed, the accumulations separated therefrom and then returned for further use.

Having thus described our invention what we claim as new and desire to secure by Letters Patent, is—

In a bee hive of the character described, the combination of a plurality of upper and lower cleats with a plurality of juxtaposed grooved plates, each comprising a head, tongues formed with short strips carried on said head and adapted to enter said grooves, said heads adapted to rest upon the upper cleats and the corners of the lower edges of said plates recessed or removed for permitting engagement with the lower cleats, and knob extensions formed in substantially the center of said plates adapted to make contact with the adjacent plate for spacing the 105 several plates, substantially as described and for the purpose set forth.

In testimony whereof we have affixed our signatures.

FRANK PELC.
STEFANIA PELC.

Witness:

A. B. COCHRAN.
